UNITED STATES PATENT OFFICE.

BENJAMIN H. GATTON, OF BATH, ILLINOIS.

GRAIN-CAR DOOR.

SPECIFICATION forming part of Letters Patent No. 289,247, dated November 27, 1883.

Application filed May 14, 1883. (No model.)

To all whom it may concern:

Be it known that I, BENJAMIN H. GATTON, of Bath, county of Mason, Illinois, have invented a new and Improved Grain-Car Door, 5 of which the following is a full, clear, and exact description.

My improved grain-car door consists of a plate of boiler-iron or other suitable material arranged in slideways inside of the common door, 10 and extending through one of the door-posts into the space between the outer and inner casings of the shell of the car-body, whereinto said iron door is shifted by sliding it back when it is required to be opened, and the door-post 15 against which the end of the door abuts when shut has a cleat, which, together with the outer walls of the groove in the floor and of the slot in the post, through which the door slides, supports the door against the pressure of the grain, 20 the arrangement being very simple to construct and also to operate, all as hereinafter fully described.

Reference is to be had to the accompanying drawings, forming part of this specification, 25 in which similar letters of reference indicate corresponding parts in both figures.

Figure 1 is an inside perspective elevation of one of the sides of a grain-car, showing my improved grain-door arrangement, part of the 30 inner casing of the said side being broken out to show the space in which the door slides; and Fig. 2 is a side elevation of the door alone.

I take a sheet of boiler-plate or other suitable material, of sufficient thickness to have 35 ample strength for resisting the pressure of the grain, and arrange a groove, *b*, for it along the

door-sill, and also along the car-sill past the post *c*, through which I make a slot, *d*, to allow of sliding the door *a* into and out of the space *e* between the inner ceiling, *f*, and the outer casing, *g*, of the car-body. At *h*, I arrange a cleat, against which the end of the door shutting against post *i* rests, to be supported against the pressure of the grain, and at *j*, I make a notch in the upper edge of the grain-door, to fasten it, shut or open, by a pin, *k*, that is to be inserted in a hole of post *c*, arranged so that the pin crosses the door in the notch, and thus firmly secures it.

To facilitate the sliding of the door forward 50 and backward in its ways, I attach a chain or chains, *l*, to the upper edge of said door, and near the front end.

This door is to be used inside of and together with the ordinary door, which slides in a similar manner on the outside of the car.

Having thus described my invention, I claim as new and desire to secure by Letters Patent—

A grain-car door consisting of a metal plate, *a*, arranged in a groove, *b*, of the door-sill, and in a slot, *d*, in one of the door-posts, combined with the cleat *h* on the other post, the groove *b* being extended along the car-sill beyond the post, and between the siding *g* and the ceiling *f*, and said door having a notch, *j*, for the fastening-pin, and a chain, *l*, for operating it, all substantially as herein described.

BENJAMIN H. GATTON.
